United States Patent Office

Des. 203,226
Patented Dec. 14, 1965

203,226

JUG

Martin Schnur, 220 St. Cloud Ave., West Orange, N.J.,
and Mel Appel, 9 Nottingham Road, Livingston, N.J.

Filed Dec. 18, 1964, Ser. No. 83,084

Term of patent 14 years

(Cl. D58—5)

FIG. 1.

FIG. 2.

FIG. 3.

FIG. 4.

FIG. 1 is a side elevational view of a jug, showing our new design;

FIG. 2 is a side elevational view of the jug when rotated 45 degrees from the position seen in FIG. 1;

FIG. 3 is another side elevational view of the jug when rotated another 45 degrees in the same direction; and

FIG. 4 is a top plan view of the jug.

We claim:

The ornamental design for a jug, as shown.
